UNITED STATES PATENT OFFICE

ALBERT OLSON, OF MINNEAPOLIS, MINNESOTA

DESIGN FOR A TOY

Application filed July 27, 1931. Serial No. 40,693. Term of patent 7 years.

To all whom it may concern:

Be it known that I, ALBERT OLSON, a citizen of the United States, residing at Minneapolis, in the county of Hennepin and State of Minnesota, have invented a new, original, and ornamental Design for Toy, of which the following is a specification, reference being had to the accompanying drawings, forming part thereof.

Fig. 1 is a side elevation of the toy.
Fig. 2 is a plan or top view of the toy.
The drawing is lined to indicate color.
I claim:
The ornamental design for a toy, as shown and described.

ALBERT OLSON.
